Inventor

Joaquin Ramos Roa.

By Watson E. Coleman

Attorney

UNITED STATES PATENT OFFICE.

JOAQUIN RAMOS ROA, OF MEXICO, MEXICO.

SHOE.

Application filed September 27, 1922. Serial No. 590,928.

To all whom it may concern:

Be it known that I, JOAQUIN RAMOS ROA, a citizen of the Republic of Mexico, residing at Mexico, D. F., Mexico, have invented 5 certain new and useful Improvements in Shoes, of which the following is a specification, reference being had to the accompanying drawings.

This invention relates to shoes, and particularly to metal shoes.

The general object of the invention is to provide a metal shoe which shall have sufficient strength and rigidity but which shall have the sole and upper so constructed that 15 the sole of the shoe may be bent at a point coincident with the second joint of the big toe or knuckle of the foot whereby to permit the foot to have all natural movements which are necessary to its proper function- 20 ing.

A further object is to so construct the shoe that the sole is formed in two sections hinged to each other on a line beneath the second joint of the big toe, this hinge being 25 of such construction that it will permit the bending or hinged movement of the two sections of the sole in one direction but will prevent any movement of the sole in the other direction beyond a predetermined 30 point, and to so construct the upper that it will permit this movement of the sole.

Other objects will appear in the course of the following description.

My invention is illustrated in the accompanying drawings, wherein:—

Figure 1 is a side elevation of a shoe constructed in accordance with my invention;

Figure 2 is an under side plan view of a 40 shoe having a sectional hinged sole;

Figure 3 is a detail section through the hinged portion of the sole and a part of the upper;

Figure 4 is a like view to Figure 3, but 45 showing a modification of the means for hinging the two sections of the sole to each other.

Referring to these drawings, it will be seen that I have illustrated a low shoe of 50 ordinary construction, though I do not wish to be limited to the use of my invention in a low shoe, as the invention might be used on high shoes, slippers or sandals. The upper

and counter 10 of the shoe are to be constructed in any suitable manner of metal, 55 or metal alloy. The upper forward of the counter is formed in two sections 11 and 12 separated from each other by a space 13, the edges of the two sections 11 and 12 defining the space 13 being downwardly convergent. The sole of the shoe may be formed of aluminum of any desired thickness or of any other suitable metal and, as illustrated in Figure 1, this sole 14 is formed 60 of one piece of relatively flexible metal so 65 that the shoe will bend at the point immediately below the space 13.

In Figure 2, I have shown a sole which is formed in two sections 15 and 15^a, these sections being relatively rigid but being 70 connected by a hinged joint disposed immediately beneath the lower end of the opening 13, the hinged joint extending entirely across the sole.

I have shown the two sections as being 75 formed with interdentated portions 16 though which passes a pintle 17. The adjacent edges of these portions are beveled, as at 18, so that the teeth or lugs on one section will fit beneath the overhanging portion 80 of the next adjacent section. Thus these two sections 15 and 15^a can move upward relative to each other but are limited in their downward movement to a position in the same plane. I do not wish to be limited 85 to this manner of making the hinge, as it is obvious that, as illustrated in Figure 4, a strip 19 may constitute the hinge and be welded, riveted or otherwise connected to the sections 14 and 15. The instep 20 is of 90 thin, rigid metal and the heel 21 may be of any suitable construction, though it is preferably an elastic heel.

As before remarked, the hinge, whether this hinge is formed of interdentated strips 95 connected by a pintle or by weakening the metal at a point beneath the lower end of the space 13 or in any other way, is disposed transversely of the sole of the shoe on a line coincident with the second joint of the 100 big toe, and inasmuch as the space 13 has its lower end located at this point, it is obvious that the foot can flex at the second joint of the big toe in the usual manner, the two sections of the upper moving toward 105 each other at this time. This permits the

foot to have all the usual or natural movements incident to walking, dancing, running or other exercise.

The metal body of the shoe will preferably be made of thin aluminum or any other metal or alloy, but the shoe may be even made of wood or other rigid material. The body may be covered inside or outside with leather, cloth or other suitable material or not covered if desired. The bodies of the shoes may be sold to manufacturers to be covered by them, or these shoes may be left uncovered and painted, enameled or otherwise decorated. Every part of the shoe is rigid except where the sole is hinged or otherwise made flexible to let the sole flex in walking. It is obvious that the shoe may be of any ornamental form or material and that minor modifications might be made in the details of construction and arrangement of parts without departing from the spirit of the invention as defined in the appended claims.

I claim:

1. A shoe comprising a sole formed of sections hingedly connected along a line at the ball of the foot whereby the forwardmost section will be capable of upward swinging with respect to the rearmost section, and a metal upper including a rear portion carried by the rear section of the sole and having its forward edge terminating at the hinge joint and inclined upwardly and rearwardly, the upper further including a toe portion carried by the forward section of the sole with its rear edge terminating at the hinge joint and inclined upwardly and forwardly, the inclination of the adjacent ends of the portions of the upper defining a V-shaped opening between the portions, and a strip of flexible material secured within the upper and overlapping the V-shaped opening between the ends thereof, said inclined edges being adapted to abuttingly engage for limiting upward swinging movement of the sole sections with respect to each other.

2. A shoe having an upper constructed of metal and a sole formed of metallic sections joined at a line transversely beneath the ball portion of the shoe, the upper being cut away at a point above the joint between the sole sections, the edges of said cut away portion converging downwardly, engagement of said edges limiting upward flexing movement of the sole, the joint between the sole sections consisting of a plurality of interfitting teeth and a pintle passing through all the teeth, the upper edges of the teeth being beveled and the portions of the sole sections engaged by the teeth being correspondingly beveled, the coacting beveled surfaces operating to prevent downward flexing of the sole to a position beyond that in which both sole sections will lie in the same plane.

3. A shoe of the character described comprising a sole formed in two sections, the joint between said sections extending transversely across the sole at a point approximately beneath the second joint of the big toe, the sections being operatively hinged to each other for upward movement but having limited downward movement to a position where the sections are in the same plane, the upper being cut away immediately above said hinged joint, said cut away portion being relatively wide at the top of the shoe and converging downward to the joint.

4. A shoe of the character described comprising a sole formed in two sections, the joint between said sections extending transversely across the sole at a point approximately beneath the second joint of the big toe, the adjacent edges of the sections being formed to provide interfitting interdentated portions, the confronting edges of the sole at said interdentated portions being complementarily beveled, and a pintle extending through said interdentated portions.

In testimony whereof I hereunto affix my signature.

JOAQUIN RAMOS ROA.
